UNITED STATES PATENT OFFICE.

BERTRAM NEILL, OF NORWALK, CALIFORNIA.

BOILER AND FURNACE ARCH.

Application filed February 19, 1925. Serial No. 10,306.

This invention relates to improvements in brick arches for boilers, furnaces and the like.

Heretofore it has been common practice 5 to provide an arcuate steel frame having its ends bent downwardly to provide abutments for the ends of a row of bricks adapted to be clamped within the frame in forming an arch. This construction permitted the 10 bricks to be inserted into the frame by springing apart the abutment forming ends, but was found disadvantageous for the reason that the brick would vary in size and for this reason chipping of the brick was 15 frequently necessary.

It is therefore an object of this invention to provide an improved frame or bracket for holding brick in forming an arch, wherein adjustment of the abutments is provided 20 so that chipping of the bricks is unnecessary.

With the foregoing and other objects in view which will be made manifest in the following detailed description and pointed out in the appended claims, reference is had 25 to the accompanying drawings for an illustrative embodiment of the invention, wherein:

Figure 1 is a vertical section through a boiler mounting, showing the boiler in elevation and showing the arch formed with the improved frame or bracket in applied position;

Fig. 2 is a vertical section through the improved frame or bracket;

Fig. 3 is a view in elevation taken in the direction of the arrow 3 upon Fig. 2;

Fig. 4 is a perspective view of the arcuate member employed in forming the frame or bracket;

Fig. 5 is a view in side elevation of the movable member forming a part of the frame; and

Fig. 6 is a view in elevation taken substantially in the direction of the arrow 6 45 upon Fig. 5.

Referring to the accompanying drawings wherein similar reference characters designate similar parts throughout, the boiler is designated at B, which is provided with return tubes 10. 11 designates one of the heads of the boiler, which may be provided with certain fixtures, as, for example, a fuse plug 12, a manhole bracket 13, and other fixtures 14. The reference character 15 designates one of the masonry walls of the boiler mounting, and in the illustration, the

wall 15 may be considered as the rear wall of the boiler mounting, which is to be provided with a brick arch for directing flame and hot gases backwardly through the return tubes 10. This arch is designated at 60 16. In forming the arch, the frame of the improved construction consists of an arcuate member 17, which is of a suitable width and bent preferably upon an arc of a true 65 circle. One end of the arcuate member 17 is bent downwardly, as at 18, providing an abutment for the end of the row of bricks 19. The lower end of the portion 18 is bent outwardly to provide an outwardly extending lip 20 for a purpose hereinafter to be described. Adjacent the other end of the arcuate member 17 there are rigidly mounted 70 studs 21 and 22, which may have their ends countersunk within the arcuate member 17, 75 or may be otherwise secured to the arcuate member. The movable member is shown in Figs. 5 and 6 and has an angular portion 23 providing an abutment opposite the abutment 18 for the other end of the row of 80 bricks 19. The portion 24 extends over the back of the arcuate member 17 a short distance and is then bent upwardly slightly, as indicated at 25. The end of the movable member is reversely bent upon itself, as at 85 26, and extends beneath the portion 27. The end of the movable member is disposed adjacent the arcuate member 17 and is beveled off, as indicated at 28. Elongated slots 90 29 and 30 are formed in the movable member and are adapted to receive the studs 21 and 22 respectively. Nuts 31 are adapted to be threaded onto the studs 21 and 22 and washers 32 may be interposed between the nuts 31 and the movable member. A wedge 95 33 is adapted to be placed between the stud 21 and the end of the movable member, presenting an inclined shoulder 28.

The assembly is as follows: The bricks forming the row 19 are positioned upon the 100 underside of the arcuate member 17. When all of the bricks are in place, the wedge 33 is driven between the stud 21 and the shoulder 28 and this draws the movable member upwardly upon the arcuate member 17 so as 105 to firmly clamp the bricks between the abutments provided at 18 and 23. When the wedge 33 has been driven home so as to tightly clamp the bricks, the nuts 31 may be screwed down by a wrench so as to firmly 110 keep the movable member in place. When the nuts 31 are tightened, the clamp or

bracket with the bricks therein may be laid upon the back wall 15, as shown in Fig. 1, with the outwardly extending lip 20 bearing upon the head 11 of the boiler B. A plurality of rows of bricks are used in forming the complete arch and a separate frame or clamp is used for each row of bricks, and is positioned with its respective row upon the wall 15. In this manner an efficient frame or bracket is provided for clamping the bricks in forming the arch, and it will be noted that it is not necessary to secure the frame or its respective row of bricks to either the boiler or to the wall 15. If any of the bricks become burnt or damaged, they may be readily removed by merely lifting the clamp from its position against the boiler and upon the wall 15.

In the course of time the lip 20 which is exposed to the flame and hot gases may become burnt, and it then is necessary to remove the frame and substitute a new arcuate member 17.

The advantage of using the arcuate member 17 with its outwardly flaring lip 20 is that the edge of the lip rests against the head of the boiler, and in this manner the lip bears upon the head only with its edge so that regardless of how many fixtures, such as indicated at 12, 13 and 14, there may be upon the head, the lip 20 is usually arranged between these fixtures. The lip 20 is preferably of the width of the width of the bricks forming the row 19, so that when the frames with the bricks therein are placed upon the rear wall 15, side by side, no opening is left between the respective rows of bricks.

It will be understood that various changes in the detail of construction may be made without departing from the spirit or scope of the invention as defined by the appended claims.

I claim:

1. A device of the class described comprising an arcuate member, against the underside of which are adapted to be placed bricks in forming an arch, means upon one end of said member providing an abutment for said bricks, studs mounted upon the other end of said member, a movable member having slots formed therein through which said studs extend, said member providing an abutment, and nuts upon said studs for tightening said movable member against movement relatively to said arcuate member.

2. A device of the class described comprising an arcuate member, against the un-

derside of which are adapted to be placed bricks in forming an arch, means upon one end of said member providing an abutment for said bricks, studs mounted upon the other end of said member, a movable member having slots formed therein, through which said studs extend, said member providing an abutment, nuts upon said studs for tightening said movable member against movement relatively to said arcuate member, and a wedge adapted to be driven between one of said studs and a shoulder upon said movable member causing said abutments to clamp upon the bricks preparatory to tightening said nuts.

3. A device of the class described comprising an arcuate member, against the underside of which are adapted to be placed bricks in forming an arch, means upon one end of said member providing an abutment for said bricks, studs mounted upon the other end of said member, a movable member having slots formed therein, through which said studs extend, said member providing an abutment, and nuts upon said studs for tightening said movable member against movement relatively to said arcuate member, one of said abutments being provided with an outwardly extending lip as and for the purpose described.

4. A device of the class described comprising an arcuate member, against the underside of which is adapted to be placed a brick in forming an arch, abutments provided adjacent each end of said arcuate member, and an outwardly extending lip provided upon one of said abutments as and for the purpose described.

5. A device of the class described comprising an arcuate member having one end bent downwardly to provide an abutment, studs mounted upon the other end of said arcuate member, a movable member providing another abutment for said arcuate member and having slots therein, through which said studs extend, said movable member having one end reversely bent upon itself to provide a shoulder, a wedge adapted to be driven between one of said studs and said shoulder, and nuts threaded on to said studs for clamping said movable member to said arcuate member when said wedge has been driven home.

In testimony whereof I have signed my name to this specification.

BERTRAM NEILL
